RUBBER COATED PLYWOOD FOR ROAD MATERIAL

Clarence U. Gramelspacher, Jasper, Ind.

Application August 16, 1938, Serial No. 225,131

5 Claims. (Cl. 94—15)

My invention relates to covers for highways. It is the object of my invention to provide a plywood covering for highways coated with vulcanized rubber to prevent skidding of automobiles.

5 I have found that wet rubber, such as a wet rubber tire, engaging a wet rubber surface will not skid. There is a high frictional resistance between the two rubber surfaces, even though they are wet. This is not true of a wet concrete, 10 brick or asphalt surface engaged by a rubber tire.

It is therefore the object of my invention to provide a strong resilient base, preferably in sections, of plywood, which can be firmly anchored to the underlying road base of concrete and the like, and to provide this laminated veneer body with a coating of protecting rubber, preferably 15 corrugated, on its surface.

It is a further object to provide vulcanized strips of sponge rubber on the edges so as to 20 permit of the necessary expansion and contraction.

I have found that laminated wood is tough, 25 resilient and has a long life. It is particularly desirable to arrange the sections of laminated wood with the grain transverse to the direction of travel of vehicles on the road.

It is also desirable to have the corrugations of the rubber running parallel with the grain so that these corrugations are either transverse or 30 diagonal to the line of travel on the road.

It is my object to provide such road coverings particularly at road intersections, highway crossings and at such points where traffic must stop, because of the high coefficient of friction 35 that this road covering provides for the stopping of automotive vehicles.

Referring to the drawing:

Figure 1 is a vertical section taken transversely through adjacent strips.

40 Figure 2 is a section on the line 2—2 looking in the direction of the arrows on Figure 1.

Figure 3 is a diagrammatic view of a highway partly covered, on curves and intersections, with the road covering of this invention.

45 Referring to the drawing in detail, 1 is the earth surface upon which a concrete or other road supporting layer is placed. This layer is designated 2. Mounted upon and anchored within the concrete layer 2 are the sections of rubber 50 covered plywood generally designated 3. These sections are composed of a plurality of layers of wood veneer 4, joined together by adhesive 5.

After they are so assembled with the grain of the wood preferably running lengthwise of the 55 oblong sections, the body of wood is wrapped

with a rubber covering 6. The top of this rubber covering 7 is corrugated. The side walls are provided with layers of rubber 8 of such composition that it will sponge when vulcanized.

There has already been assembled in the wood veneer layers attaching bodies 9 having enlarged heads 10 extending beyond the body of the assembly. The complete section is then placed in a vulcanizing press and vulcanized. It is now ready for assembling.

10 Holes 11 are formed in the concrete base 2. The enlarged heads 10 are inserted in the holes, which holes are preferably filled with a plastic material such as concrete or molten lead 12, so that when the material 12 hardens, the section 15 will be firmly attached to the base 2.

The bodies 9 are provided with nuts 9a so that in the event the upper rubber surface 7 wears away, then the nuts 9a may be removed and the sections of wood in the remaining rubber lifted 20 from the bodies 9. The wood sections can then be recovered with rubber, revulcanized and replaced.

Any holes left in the rubber for receiving the nuts 9a, when the sections are so replaced, can 25 be filled with rubber and vulcanized in position.

It will be understood that the plywood sections are capable of withstanding a high temperature in a vulcanizing press to have the rubber vulcanized thereto. The rubber protects the wood 30 veneer from water, freezing and dirt.

It will be further understood that the method of attaching is optional. I comprehend within my invention making the edges of these sections interlocking, either with or without the sponge 35 rubber fillers on the margins thereof.

As will be observed in Figure 3, I arrange at maximum dimension each of the blocks 3 transversely of the road. This places the corrugations 7 transversely of the road.

40 A great variety of different ways of attaching these blocks may be employed, depending upon the nature of the underlying base 2, whether it is desired to recover the wood sections, et cetera.

It will be understood that I desire to comprehend within my invention such modifications as may be necessary to adapt it to varying conditions and uses.

Having thus fully described my invention, what I claim as new and desire to secure by Letters 50 Patent, is:

1. A new article of manufacture adapted to be used as a road surfacing comprising a plywood block made up of a plurality of superimposed relatively thin layers of wood veneer adhesively 55

laminated to one another with the layers horizontally disposed parallel to the road surface, and an integral vulcanized rubber covering completely enclosing said plywood block on all surfaces thereof.

- 5 2. A new article of manufacture adapted to be used as a road surfacing comprising a plywood block made up of a plurality of superimposed relatively thin layers of wood veneer adhesively 10 laminated to one another with the layers horizontally disposed parallel to the road surface, an integral vulcanized rubber covering completely enclosing said plywood block on all surfaces thereof, and layers of vulcanized sponge rubber 15 surrounding the side walls of said rubber covered block and integral with said rubber covering.

3. In combination, in a highway, a supporting concrete base and a plurality of paving blocks mounted thereon, each of said blocks comprising 20 a plywood block made up of a plurality of superimposed relatively thin layers of wood veneer adhesively laminated to one another with the layers horizontally disposed parallel to the road surface, and an integral vulcanized rubber covering completely 25 enclosing said plywood block on all surfaces thereof, said blocks being mounted with the grain of the wood of said plywood transverse to the line of traffic.

4. In combination, in a highway, a supporting 30 base and a plurality of paving blocks mounted

thereon, each of said blocks comprising a plywood block made up of a plurality of superimposed relatively thin layers of wood veneer adhesively laminated to one another with the layers horizontally disposed parallel to the road surface, 5 an integral vulcanized rubber covering completely enclosing said plywood block on all surfaces thereof and layers of vulcanized sponge rubber surrounding the side walls of said rubber covered block and integral with said rubber covering, 10 said blocks being mounted with the sponge rubber side walls of adjacent blocks contacting one another, said sponge rubber allowing for expansion and contraction between adjacent blocks.

5. In combination, in a highway, a supporting 15 base and a plurality of paving blocks mounted thereon, each of said blocks comprising a plywood block made up of a plurality of superimposed relatively thin layers of wood veneer adhesively laminated to one another with the layers horizontally 20 disposed parallel to the road surface, an integral vulcanized rubber covering completely enclosing said plywood block on all surfaces thereof, and vertical attaching means secured into said blocks and extending through at least a portion of said 25 lamination downwardly into and secured into said base, said attaching means being provided with means preventing upward movement of said blocks.

CLARENCE U. GRAMELSPACHER. 30
